US0D1112732S

(12) **United States Design Patent** (10) **Patent No.:** **US D1,112,732 S**
(45) **Date of Patent:** **** Feb. 10, 2026**

(54) **CONTROL PLATFORM**

(71) Applicant: **Pirum Solmed Ltd**, Limassol (CY)

(72) Inventor: **Carmen Roxana Serfezi**, Limassol (CY)

(73) Assignee: **Pirum Solmed Ltd**, Limassol (CY)

(**) Term: **15 Years**

(21) Appl. No.: **29/853,851**

(22) Filed: **Sep. 20, 2022**

(57) **CLAIM**

The ornamental design for a control platform as shown and described.

DESCRIPTION

FIG. 1 is a front perspective view of the control platform showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a partial enlarged view taken from FIG. 1;

FIG. 9 is a cross-sectional view taken through line 9-9 from FIG. 5;

FIG. 10 is a cross-sectional perspective view taken through line 10-11 from FIG. 3;

FIG. 11 is a cross-sectional perspective view taken through line 11-11 from FIG. 2;

FIG. 12 is a bottom perspective view; and,

FIG. 13 is a bottom side perspective view thereof.

The dashed lines shown in FIGS. 1 and 8 depict boundaries of the enlarged view indicators and form no part of the claimed design.

1 Claim, 13 Drawing Sheets
